Primary Examiner—Alan P. Douglas*Assistant Examiner*—Cynthia E. Ramirez*Attorney, Agent, or Firm*—Roger S. Dybvig**[57]****CLAIM**

The ornamental design for a soleplate for a steam iron, as shown and described.

DESCRIPTION

FIG. 1 is a perspective view as seen from the bottom, rear, and right side of a soleplate for a steam iron showing my new design;

FIG. 2 is a bottom plan view thereof;

FIG. 3 is a left side elevational view thereof, the right side elevational view being a mirror image of the left side elevational view;

FIG. 4 is a front elevational view thereof; and,

FIG. 5 is a rear elevational view thereof.

The top plan view for the soleplate for a steam iron has been omitted as the top is not visible during normal use.

The broken lines in FIG. 1 showing the body of a steam iron are used for illustrative purposes only and form no part of the claimed design.
